Filed Mar. 11, 1963, Ser. No. 73,901

Term of patent 7 years

(Cl. D57—1)

FIG. 1 is a top plan view of a combined eyeglass frame and hearing aid, showing my new design;
FIG. 2 is a side elevational view thereof;
FIG. 3 is a bottom plan view thereof;
FIG. 4 is an elevational view of the opposite side thereof;
FIG. 5 is a front elevational view thereof;
FIG. 6 is a rear elevational view thereof; and
FIG. 7 is an enlarged cross-sectional view taken on the line 7—7 of FIG. 2.
The dominant features of my design reside in the portions shown in full lines.

I claim:
The ornamental design for a combined eye glass frame and hearing aid, as shown and described.
